UNITED STATES PATENT OFFICE.

ANDREW LAUNDRY, OF MONTREAL, QUEBEC, CANADA, ASSIGNOR OF ONE-HALF TO HENRY HARRISON WARREN, OF MASSENA, NEW YORK.

DIE FOR SHAPING THE CLAWS OF HAMMER-HEADS.

SPECIFICATION forming part of Letters Patent No. 398,166, dated February 19, 1889.

Application filed November 17, 1888. Serial No. 291,098. (No model.)

To all whom it may concern:

Be it known that I, ANDREW LAUNDRY, a subject of the Queen of Great Britain, residing at the city of Montreal, in the district of 5 Montreal and Province of Quebec, Canada, have invented new and useful Improvements in Apparatus for Making Hammers; and I do hereby declare that the following is a full, clear, and exact description of the same.

10 This invention has reference to improvements in the apparatus by which the claws of "claw-hammers" or carpenters' hammers are formed from blank or partly-made hammers; and the object of my improvements is 15 to enable the said claws to be formed at one operation to the proper size and bend, so that by slightly spreading the claws apart the hammer is ready for finishing by grinding and polishing without any further manipulation when the hammers are to be polished.

In the drawings hereunto annexed similar letters of reference indicate like parts.

Figure 1 is a side elevation of an apparatus embodying my invention. Fig. 2 is an end elevation of the apparatus shown in Fig. 1. Fig. 3 is a plan of the apparatus shown in Fig. 1, the pivoted lever *t* being omitted. Fig. 4 is an elevation of the roll *A* detached. Fig. 5 is an elevation of the roll *A* modified, detached. Fig. 6 is end elevation of the roll. Figs. 7 and 8 are isometrical views of hammer-blanks. Fig. 9 is an elevation of the face of the guide *f* and end view of the rest *b*. Fig. 10 is an elevation of the front face of the die *e* and rest *b*. Fig. 11 is a view of the back face of the die *e* and end of rest *b*. Fig. 12 is a longitudinal vertical section of the die *e* and guide *f*, taken on line *x*, Fig. 3. Fig. 13 is an isometrical view of the hammer as finished.

40 *a* is any suitable bed, on which is placed and secured, or made integral therewith a rest, *b*, closely filling the bases *c* and *d* of the die *e* and guide *f*, these being further secured endwise by a key or wedge, *h*.

45 The object of making the bases *c* and *d* in two parts is to save expenses in construction and repairs of the die *e* and guide *f*; otherwise they would be more rigidly connected together by making them in one piece, so 50 that, if desired, they may be made integral.

The die *e* is made with two curved surfaces, *g*, of the curve to which the outer surface of the claws *i* is to be formed, (see Fig. 13,) and with a recessed or lower surface, *l*, of the configuration and proper relative position to 55 form the inner curve to which the inner surface, *k*, is to be formed.

m is a projection, which may or may not be used, as will be hereinafter more particularly described.

60 The guide *f* is provided with two curved surfaces, *n*, parallel with the surface *g*, for the thimbles *d'*, hereinafter described, to roll upon, and a recess-surface, *o*, somewhat wider, or equal to the length of the center part, *C'*, of 65 the roll *A*, so that between the two surfaces *g* and *n* a parallel curved groove or channel, *p*, is formed the proper size for a roll, *A*, to just freely pass up and down in without any "lost motion."

70 In the face of the die *e* a properly-situated surface, *r*, is formed for resting a side of the shank of the hammer's eye against, as shown in Fig. 1.

75 On the end of the rest *b* is formed a pivot, *s*, forming the fulcrum of a lever, *t*, provided with jaws *u* to embrace and hold down in place the outer end, *a'*, of the hammer-blank while the inner end, *b'*, is being acted upon by the roll *A*. Many other contrivances may 80 be arranged for this purpose and could be at once suggested by any skilled ordinary machinist.

85 The blank-hammers are so far prepared as to have their "adz-eyes" formed in them, and the face end, *a'*, if such is to be rounded, formed as shown at *a'* in Fig. 13. The end of the blank that is to be formed into the claws is provided with a split, *b'*, as shown in Fig. 7. This is made somewhat larger than 90 the split is to be when the hammer is finished.

95 The roll *A* consists of a mandrel having an enlarged center part, *c'*. This may be parallel, as shown in Fig. 5, or it may be made with a concavity, as shown in Fig. 4. When the roll is made parallel, it rolls the outer surface, *h*, Fig. 13, of the claws flat in cross-section, and when made as shown in Fig. 4 it 100 imparts a curved outer surface, *h*, in cross-

section. On the ends h' of the roll A are placed thimbles d' , which act as friction-wheels, and are in diameter equal to the distance between the surfaces n and g .

5 e' are connecting-rods. These are attached to any desired pitman or other reciprocatingly-moved body actuated by power.

The hammer-blank having been provided with the split b' of suitable size for what is 10 desired and the said split end heated to a good red heat, it is placed in position with the dies, as shown in Fig. 1, and secured in place by the lever t . The roll A is then brought down upon it in the position shown in Fig. 1,

15 and the roll, being forced by the continued motion down to near the bottom of the groove p , rolls the end b' into the configuration that the back of the die e and roll have been designed to impart to the claws. Any surplus 20 material in the claw end of the blank-hammers is cut off at that part at which the surfaces l and g "run to nothing," or unite at the back of the die e , and such surplus falls down to the bottom of the groove p , from which it 25 is removed each time a hammer-blank is treated.

The hereinbefore-mentioned projection m if used, is by preference made in height about half of the difference of height between the 30 surfaces l and g , and is for the purpose of keeping the split b' open a positive amount. If the projection m were made in height equal to the height of the surfaces g , a fin would

be formed between the two claws, which would require much trouble to remove.

35 By actual operation I have found that very desirably-formed claws to hammers are obtained when the projection m is omitted.

The claws of the hammer, when removed from the die e after having been operated on 40 by the roll A, are finished to a perfect shape, and do not require any further manipulation, except to slightly spread them apart, which is easily done by driving a wedge in between them before they have become cold. The 45 hammers are then ready for grinding and finishing or polishing.

What I claim is as follows:

1. In an apparatus for forming the claws of carpenters' hammers, the combination of 50 the die e , having curved surfaces g and l , also having projection m , with guide f , having curved surfaces n , and roll A, arranged to be guided by the curved surfaces g and n , the whole substantially as and for the purposes 55 set forth.

2. In an apparatus for forming the claws of carpenters' hammers, the combination of the die e , having surfaces g and l , guide f , having surfaces n , and roll A, arranged to be 60 guided by the surfaces g and n , the whole substantially as and for the purposes set forth.

ANDREW LAUNDRY.
